UNITED STATES PATENT OFFICE

DAVID FISHER, OF PADEN CITY, WEST VIRGINIA, ASSIGNOR TO PADEN CITY GLASS
MANUFACTURING COMPANY, OF PADEN CITY, WEST VIRGINIA, A CORPORATION
OF WEST VIRGINIA

DESIGN FOR A TUMBLER

Application filed October 31, 1930. Serial No. 37,477. Term of patent 7 years.

To all whom it may concern:

Be it known that I, DAVID FISHER, a citizen of the United States, residing at Paden City, in the county of Wetzel and State of West Virginia, have invented a new, original, and ornamental Design for Tumbler, of which the following is a specification, reference being had to the accompanying drawing, forming part thereof.

The figure is an elevation of a tumbler, showing my new design, the tumbler being of conventional circular contour in all of its horizontal cross sections.

I claim:

The ornamental design for a tumbler, as shown and described.

DAVID FISHER.
